UNITED STATES PATENT OFFICE.

GEORGE M. OYSTER, OF WASHINGTON, DISTRICT OF COLUMBIA.

DESIGN FOR A BUTTER-PRINT.

SPECIFICATION forming part of Design No. 14,102, dated July 17, 1883.

Application filed May 29, 1883. Term of patent 14 years.

To all whom it may concern:

Be it known that I, GEORGE M. OYSTER, a citizen of the United States, residing at Washington, in the District of Columbia, have invented and produced a new and original Design for Butter-Prints, of which the following is a specification, reference being had therein to the accompanying drawings.

My invention consists in a novel design for stamping or impressing upon cakes of butter, such as are usually denominated "butter-prints" or "prints of butter," the object being to impart to the cakes or prints a hand-some appearance.

15 In the accompanying drawings, Figure 1 is a perspective view of a print or cake of butter having my design upon it. Fig. 2 is a face view of the mold or block used to produce or impress the design upon the print or cake of butter.

The design consists, primarily, of a raised figure made in the form of a four-leaved clover, with a curved stem inclosed within a raised border, the whole forming a rectangular object. The leaves, as shown in both figures, are not the ordinary red-clover leaf, which is pointed, but more nearly resemble the small white-clover leaf, being nearly heart-shaped, or slightly indented at their outer end.

25 In practice I prefer to duplicate these leaf clusters, as shown, so as to make the design

correspond in form to the cake or print of butter, which is generally oblong in form; and I also propose to use thereon the letters "G. M. O. Co." placed transversely between the two leaf clusters, as shown in the drawings, though these letters do not constitute any part of the design, which consists of the raised figure A, having the four leaves and the curved stem inclosed within the raised border B. When the two clusters are used, I prefer to arrange them as shown, with their stems curving toward the center, with the leaves nearest the ends, though it is obvious they may be arranged differently without materially changing the design or appearance.

This design, when impressed or stamped upon the cakes or prints, imparts to them a very neat appearance.

What I claim is—

The herein-described design for butter-prints, consisting of the raised figure A, having the four leaves, and a curved stem surrounded by a raised border, B, substantially as shown.

In testimony whereof I affix my signature in presence of two witnesses.

GEO. M. OYSTER.
